United States Patent [19]

Schneider et al.

[11] Patent Number: **Des. 391,182**[45] Date of Patent: ****Feb. 24, 1998****[54] INDICATOR FOR LOCATING PROXIMITY SENSORS**D. 358,561 5/1995 Webb et al. D10/104
D. 366,848 2/1996 Brown et al. .... D10/104**[75] Inventors:** Michael Schneider, Hagen; Dierk Brasse, Schalksmühle, both of Germany*Primary Examiner*—Marcus A. Jackson
Attorney, Agent, or Firm—Collard & Roe, P.C.**[73] Assignee:** Werner Turck GmbH & Co. KG, Halver, Germany**[57] CLAIM****[**] Term:** **14 Years**

The ornamental design for a an indicator for locating proximity sensors, as shown and described.

[21] Appl. No.: **66,934****DESCRIPTION****[22] Filed:** **Feb. 24, 1997**

FIG. 1 is a left side view of a device for an indicator for locating proximity sensors showing my new design, with the wires broken away to indicate indeterminate length;

[30] Foreign Application Priority Data

FIG. 2 is a bottom view thereof;

Aug. 23, 1996 [DE] Germany ..... M 96 07 367.5

FIG. 3 is a rear view thereof;

[51] LOC (6) Cl. **10-05**

FIG. 4 is a top view thereof;

[52] U.S. Cl. **D10/104**

FIG. 5 is a right side view thereof;

[58] Field of Search D10/104, 109,

FIG. 6 is a front view thereof; and,

D10/111, 114, 121; 340/906, 907, 908,
908.1, 909, 910, 911, 915

FIG. 7 is a perspective view thereof.
